UNITED STATES PATENT OFFICE.

EDWARD E. JOHNSON, OF ST. PAUL, MINNESOTA.

DEEP-WELL PUMP.

Application filed June 13, 1919. Serial No. 303,903.

To all whom it may concern:

Be it known that I, EDWARD E. JOHNSON, a citizen of the United States, residing at St. Paul, in the county of Ramsey and State 5 of Minnesota, have invented certain new and useful improvements in Deep-Well Pumps, of which the following is a specification.

My invention relates to deep well pumps 10 and an object is to provide a pump of this character having a pump head containing mechanism for operating pump plungers, the operating mechanism being so constructed that a single unit may be assembled 15 in place on the pump head when it is desired to employ a single plunger and two or more operating units may be assembled in cooperative relationship with each other on the pump head when it is desired to employ two 20 or more plungers for operation in the pump barrel. A further object is to so construct the operating mechanism that a plurality of units may be readily assembled for co-action in proper timed relation for operating 25 the desired number of plungers with their relative movements properly timed.

The full objects and advantages of my invention will appear in connection with the detailed description thereof and the novel 30 features embodied in my inventive idea will be particularly pointed out in the claims.

Referring to the accompanying drawings, which illustrate the application of my invention in one form,—

Fig. 1 is a view in a vertical sectional elevation. Fig. 2 is a part sectional and part elevational view taken at right angles to the position shown in Fig. 1. Fig. 3 is a view on an enlarged scale in section on the line 3—3 of Fig. 2. In the particular embodiment shown in the drawings, the construction is that of a triplex or three-stroke pump in which three plungers are used. The character 10 designates a solid reciprocating rod to the lower end of which the lower pump plunger is secured. A hollow reciprocating rod 12 surrounds and is adapted to slide relatively to the solid rod 10, and an intermediate pump plunger is secured to the lower end of the hollow rod 12. A hollow rod 14 surrounds and is adapted to slide relatively to the hollow rod 12 and an upper pump plunger is secured to the lower end of the hollow rod 14. The 55 solid rod 10 at its upper end is journaled upon a crank-pin 16. The hollow rod 12 at its upper end is secured to a cross-head 18 to which the lower ends of rods 20 and 22 are secured. These latter rods are arranged in offset relation as shown in Fig. 3 and 60 their upper ends are secured to a bearing member 24 which is journaled on a crank-pin 26. The hollow rod 14 at its upper end is secured to a cross-head 28 to which the lower ends of rods 30 and 32 are secured. These 65 latter rods are arranged in offset relation in reversed position relatively to the rods 20 and 22, as shown in Fig. 3, and the upper ends of the rods 30 and 32 are secured to a bearing member 34 which is journaled on 70 a crank-pin 36. The pump head is provided with bearings for a transverse driving shaft 38 to which are secured two pinions 40 meshing with external ring gears 42 rotatably mounted upon a circular series of roller 75 bearings 44 which are located between an offset inner wall of the gears 40 and the outer wall of internal ring gears 46 which are rigidly secured to the gear casing. Spur gears 48 mesh with the internal gears 80 46, the diameter of these spur gears being one-half the diameter of the internal gears. The spur gears 48 are rotatably mounted on studs 50 attached to the external gears 42 between their centers and peripheries. The 85 two spur gears 48 are connected by the crank-pin 26 previously referred to, which is so positioned that the center thereof extends between the pitch lines of the spur gears 48. In operation the rotation of the exter- 90 nal gears 42 carries the spur gears 48 in an annular path, thereby rolling them around within the internal gears 46. Since the latter are twice the diameter of the spur gears 48, the crank-pin 26 is caused to move up 95 and down in a straight line and reciprocate the attached pump rod. In case it is desired to use only one pump plunger a single operating unit, such as described, is employed and the solid pump rod 10 is attached 100 to the bearing member which is journaled on the crank-pin. If it is desired to use two pump plungers another operating unit, designated by the character A, similar to that just described and designated generally by 105 the character B is used, the two units being assembled so that the external gears of the two units mesh with each other for rotation in opposite directions. In such case the solid pump rod 10 is attached to the crank- 110

pin 16 of the unit A and the hollow pump rod 12 is attached to the crank-pin of the superimposed unit B, and the external gears of the two units are meshed so that the two 5 crank-pins reciprocate oppositely, or toward and away from each other alternately. If it is desired to use three pump plungers a third unit, designated by the character C is superimposed upon unit B with the external gears 10 of the two units meshing with each other so that the gears are driven in opposite directions. In this case the hollow pump rod 14 is attached to the crank-pin 36 of the unit C and the external gears of the three 15 units are meshed in such position that the crank-pins of the three units reciprocate with a properly timed relationship.

I claim:

1. In combination with a base and two or 20 more pump rods mounted for reciprocation therethrough, mutually detachable pump operating units corresponding in number to the number of pump rods, mounted upon said base and in tandem series upon one another, each having independent connection with one only of said pump rods, and means for driving one of said units directly from a source of power and all of the other units from the driven unit.
2. In combination with a base and two or 30 more pump rods mounted for reciprocation therethrough, mutually detachable pump operating units corresponding in number to the number of pump rods, mounted upon 35 said base and in tandem series upon one another, each having independent connection with one only of said pump rods, and means for driving one of said units directly from a source of power and all of the other units 40 from the driven unit, all of said units being interchangeable and each adapted to be mounted directly upon the base.
3. A pump comprising a pump head and 45 two or more pump rods, operating units adapted to be mounted in said pump head each separable from and independent of the other and each provided with unitary and complete means for operating a pump rod, each of said units including an external gear 50 constructed to mesh with the corresponding gear of another unit whereby one or more of said units may be assembled in said pump head for actuation from a common source of power, and means associated with each of 55 said units for connection with a pump rod, whereby a varying number of pump rods may be used, the same in number as the operating units.
4. A pump comprising a pump head and 60 two or more pump rods, operating units adapted to be mounted in said pump head each separable from and independent of the other and each provided with unitary and complete means for operating a pump rod, 65 each of said units including an external

gear, a spur gear rotatably mounted on said external gear, a fixed internal gear with which said spur gear meshes, and a crank pin secured to said spur gear, said external gear being constructed to mesh with the corresponding gear of another unit whereby one or more of said units may be assembled in said pump head for actuation from a common source of power, and means for connecting each of said crank pins with a pump 70 rod whereby a varying number of pump rods may be used, the same in number as the operating units.

5. In combination with a base and two or 75 more pump rods mounted for reciprocation therethrough, operating units for said pump rods each comprising an external gear and mechanism connected therewith for independent connection with a pump rod to reciprocate the same, each of said units comprising a housing embodying plane-surfaced flanged top and bottom portions for interchangeable connection with the base and with one another, and having openings through said top and bottom portions 80 through which the external gears of adjacent units may extend into mesh.

6. In combination with a base and two or 85 more pump rods mounted for reciprocation therethrough, operating units for said pump rods each provided with unitary and complete means for operating one only of said pump rods, and each being provided with a housing embodying plane-surfaced flanged top and bottom portions for interchangeable 90 connection with the base and with one another.

7. In combination with a base adapted to have one or more pump rods mounted for reciprocation therethrough, a pump operating unit mounted on said base and provided with unitary and complete means for operating one only of said pump rods, said unit having means for having mounted thereon and being driven therefrom, a second detachable operating unit adapted to have connection with and adapted to operate a second pump rod.

8. In combination with a base adapted to have one or more pump rods mounted for 115 reciprocation therethrough, a pump operating unit provided with unitary and complete means for operating one only of said pump rods, said unit having a housing embodying plane-surfaced flanged top and bottom portions for mounting the same upon the base and to receive upon the top portion thereof another similar operating unit adapted to have connection with and adapted to operate another pump rod, and 120 means in each of said units adapted to cooperate when the same are so connected together whereby one of said units is driven from the other.

9. In combination with a base and two or 130

more pump rods mounted for reciprocation therethrough, operating units for said pump rods each provided with unitary and complete means for operating one only of said 5 pump rods, and each having a similarly constructed housing with top and bottom openings therein, and means for securing said units through said housings one upon the base and the others thereupon and upon each other so that the united housings form in effect a single enclosing and supporting member with the several pump rods extending therethrough each to its respective operating unit.

In testimony whereof I hereunto affix my 15 signature.

EDWARD E. JOHNSON
